UNITED STATES PATENT OFFICE.

WILLOUGHBY STATHAM SMITH, OF BENCHAMS, NEWTON POPPLEFORD, AND ALFRED DEVER SHUTER, OF HARROW-ON-THE-HILL, ENGLAND.

APPARATUS FOR LAYING OR GUIDING ROPES, CHAINS, AND CABLES.

Application filed May 7, 1927, Serial No. 189,734, and in Great Britain February 8, 1927.

This invention relates to improvements in apparatus for laying or guiding ropes, chains, and cables on and off the drum or drums of a winch or the like.

5 In the manufacture and use of cables and ropes, it is frequently necessary to pass the cable or a part thereof around a winch drum about which it is given one or more turns for the purpose of hauling or holding the 10 cable, and in order to move the turn or turns over a surface of the drum to make way for the oncoming cable, a guide known as a splitting or fleeting knife is employed, which is set at an angle to the path of the 15 cable so causing the latter to be pushed aside to make way for the oncoming cable.

Such an arrangement, however, has the disadvantage that friction is produced between the knife and the cable with consequent wear on both, or possible injury to the 20 cable. Hence, the fleeting knife is sometimes replaced by a roller. But, owing to the pressure of this roller bearing on a very small area of the side of the cable, a flat is 25 liable to be produced in its path.

Yet another method of causing the turns to shift on a winch drum is to make the drum conical or partly conical, so that the turns of cable continuously slip down onto 30 the smaller diameter. This method has the disadvantage that circumferential slipping is liable to take place.

It is the object of this invention to overcome these difficulties.

35 According to this invention a ring is loosely mounted on the drum, which is preferably cylindrical, the internal diameter of the ring being larger than that of the drum at its periphery, so that the ring, owing to 40 the thrust of the oncoming cable against it, may tilt and set itself at an angle to the axis of the drum, means being provided to prevent lateral movement of the ring along the drum in a direction away from the 45 cable.

Preferably a block or roller is provided, which engages the ring on the side opposite to that of the cable, and located on the side of the drum away from the point of 50 contact of the oncoming cable in such a position that it bears against the ring at a point about 90° in advance thereof.

The angle of tilt of the ring will depend upon the difference in diameters of the ring

and drum but it has been found preferable 55 to limit this angle by means of a second roller placed diametrically opposite the first one.

It should be understood that any number 60 of such rollers may be provided located around the drum, but two rollers have been found to be sufficient since if the ring is allowed to tilt freely about an axis joining the two rollers it adjusts itself automatically in such a way as to distribute the pressure on 65 the cable over the widest possible arc, thus reducing the intensity of stress to a minimum.

The rollers may be mounted in such a manner as to be adjustable and carried on 70 pivotally mounted arms or alternatively they may be carried in a frame adapted to rotate about a vertical axis located in a plane passing through the axis of the drum and preferably at the intersection of the 75 latter with the virtual axis of the ring, the angle of set of the frame being adjustable.

In this latter arrangement which is especially suitable where it is desired to reverse the direction of rotation, the ring and rollers are preferably formed as truncated cones whose apices meet at the point of intersection of their axes of rotation whereby a 80 true rolling motion is obtained.

In another construction, the rollers may 85 be replaced by a second ring carried by the main ring, the two rings being provided with ball races so that main ring may freely rotate with respect to the second ring 90 against whose rear surface bear adjusting screws.

The invention is illustrated in the accompanying drawings in which Figure 1 is an elevation of a winch drum on which is mounted a ring shown in section. Figures 95 2 and 3 are an elevation and plan showing a winch constructed in accordance with the invention.

Figure 4 is a plan of a modification. Figure 5 is a section on the line 5-5 of Figure 100 4. Figures 6 and 7 are similar views of a further modification. Figure 8 is a section to a larger scale through a part of the ring.

Referring to the drawings, 1 is a drum on 105 which is mounted a ring 2 whose internal diameter is larger than that of the drum at its periphery.

In order to control the ring 2, rollers 4 are

provided carried by arms 5 pivotally mounted to the frame 6 of the winch. The position of the arm 5 may be adjusted by means of screws 7 having operating handles

5 8.

The drum is mounted to rotate with its shaft 9 and as the oncoming cable shown at 10 passes around the drum which revolves in the direction of the arrow it tends to push

10 the ring off the drum.

This tendency, however, is resisted by the rollers 4 which engage the rear surface of the ring so causing the turns to push each other across the surface of the drum as the

15 oncoming cable engages the ring.

In order that the bore of the ring where it engages the drum, may make complete contact therewith, it is tapered, as shown at 11.

Referring now to Figures 4 and 5, the 20 rollers 18 are shown mounted in a frame 12, pivotally mounted at 13 in a vertical plane passing through the point of intersection of the axis of the drum and the virtual axis of the ring, whereby the axes of the rollers are 25 always normal to that of the ring.

The frame is held in position by adjusting screws 14.

In order to obtain a true rolling action between the ring and the rollers, they are 30 formed as truncated cones whose apices meet at the point of intersection of their centre lines.

Referring now to Figures 6, 7 and 8, the ring is shown provided with a secondary or 35 thrust ring 15 whereby the rollers may be eliminated. Located between the front of the ring and the secondary ring 15, are balls 16 so that the front may freely rotate with respect to the thrust ring, which is engaged 40 by screw bolts 17 so that the position of the ring may be adjusted.

A stop or stops (not shown) may be provided to prevent the rotation of the secondary ring.

45 It is obvious that the invention may be applied to cables, chains, ropes, and similar members, and in the claims the expression "continuously flexible member" is intended to cover all such equivalent devices. The 50 reference to a drum is also intended to cover any equivalent rotatable member.

What we claim is:—

1. In apparatus for guiding a continuously flexible member on and off a drum, the 55 combination with the drum of a ring loosely mounted thereon, and having an internal diameter larger than that of the drum at its periphery, and means for preventing lateral movement of the ring along the drum in a direction away from the flexible member.

2. In apparatus for guiding a continuously flexible member on and off a drum, the

60 combination with the drum of a ring loosely mounted thereon, and having an internal diameter larger than that of the drum at its

periphery, and a plurality of rollers engaging the ring to prevent lateral movement of the ring along the drum in a direction away from the flexible member.

3. In apparatus for guiding a continuously flexible member on and off a drum, the combination with the drum of a ring loosely mounted thereon and having an internal diameter larger than that of the drum at its periphery, a plurality of rollers engaging 75 the ring to prevent lateral movement of the ring along the drum in a direction away from the flexible member, and means for adjusting the position of the rollers.

4. In apparatus for guiding a continuously flexible member on and off a drum, the combination with the drum of a ring loosely mounted thereon and having an internal diameter larger than that of the drum at its periphery, a frame, a plurality of rollers 80 mounted in said frame, said rollers engaging the ring to prevent lateral movement of the ring along the drum in a direction away from the flexible member, and means for adjusting the position of the frame. 90

5. In apparatus for guiding a continuously flexible member on and off a drum, the combination with the drum of a ring loosely mounted thereon and having an internal diameter larger than that of the drum at its periphery, and a roller engaging the ring 95 and located on the side of the drum remote from the point of contact of the oncoming flexible member.

6. In apparatus for guiding a continuously flexible member on and off a drum, the combination with the drum of a ring loosely mounted thereon and having an internal diameter larger than that of the drum at its periphery, and two rollers engaging the ring 100 and located diametrically opposite one another. 105

7. In apparatus for guiding a continuously flexible member on and off a drum, the combination with the drum of a ring loosely 110 mounted thereon and having an internal diameter larger than that of the drum at its periphery, and two rollers engaging the ring and located diametrically opposite one another, one of said rollers being located on 115 the side of the drum remote from the point of contact of the oncoming flexible member.

8. In apparatus for guiding a continuously flexible member on and off a drum, the combination with the drum of a ring loosely 120 mounted thereon and having an internal diameter larger than that of the drum at its periphery, and adjustable means for preventing lateral movement of the ring along the drum in a direction away from the flexible member. 125

9. In apparatus for guiding a continuously flexible member on and off a drum, the combination with the drum of a ring loosely 130 mounted thereon and having an internal

diameter larger than that of the drum at its periphery, a roller engaging the ring and located on the side of the drum remote from the point of contact of the oncoming flexible member, and means for adjusting the position of the roller.

10. In apparatus for guiding a continuously flexible member on and off a drum, the combination with the drum of a ring loosely mounted thereon and having an internal diameter larger than that of the drum at its periphery, two rollers engaging the ring and located diametrically opposite one another, and means for adjusting the position of the 15 rollers.

11. In apparatus for guiding a continuously flexible member on and off a drum, the combination with the drum of a ring loosely mounted thereon and having an internal 20 diameter larger than that of the drum at its periphery, two rollers engaging the ring and located diametrically opposite one another, one of said rollers being located on the side of the drum remote from the point 25 of contact of the oncoming flexible member, and means for adjusting the position of the rollers.

12. In apparatus for guiding a continuously flexible member on and off a drum, the 30 combination with the drum of a ring loosely mounted thereon and having an internal diameter larger than that of the drum at its periphery, a frame, two rollers mounted in said frame, said rollers engaging the ring and 35 and located diametrically opposite one an-

other, and means for adjusting the position of the frame.

13. In apparatus for guiding a continuously flexible member on and off a drum, the combination with the drum of a ring loosely 40 mounted thereon and having an internal diameter larger than that of the drum at its periphery, a frame, two rollers mounted in said frame capable of rotation about a vertical axis passing through the axis of the 45 drum, said rollers engaging the ring and located diametrically opposite one another, and means for adjusting said frame about its axis.

14. In apparatus for guiding a continuously flexible member on and off a drum, the combination with the drum of a ring loosely 50 mounted thereon and having an internal diameter larger than that of the drum at its periphery, a frame, two rollers mounted in 55 said frame capable of rotation about a vertical axis passing through the axis of the drum, said rollers engaging the ring and located diametrically opposite one another, one of said rollers being located on the side 60 of the drum remote from the point of contact of the oncoming flexible member, and means for adjusting said frame about its axis.

In testimony that we claim the foregoing 65 as our invention, we have signed our names this 29th day of April, 1927.

WILLOUGHBY STATHAM SMITH.
ALFRED DEVER SHUTER.
